This invention consists in the construction and arrangement of a novel adjustable desk or table attachment for chairs, which may be applied to any ordinary chair, and used for the purposes of writing, reading, &c.

Referring to the accompanying drawing illustrating this invention, A represents a chair; B, a pair of legs, pivoted at their upper ends to a pair of arms, b, which are pivoted or attached to a transverse bar, c. C represents a desk or table-leaf, placed across the arms b in front of the chair. It is pivoted to one of said arms, so that it may be turned around, as desired. D D are intended to represent adjustable clasps for securing the bar c to the back of the chair, as shown in the drawing.

The joints of the described attachment are pivoted so that the height and incline of the desk-leaf may be varied to suit the occupant of the chair; also, to allow the apparatus to be folded up behind the chair.

I claim as my invention.

The improved adjustable desk or table attachment for chairs, having the legs B, pivoted arms b, pivoted leaf c, and adjustable clasps or fastenings D, as described.

In testimony that I claim the above I have hereunto subscribed my name in the presence of two witnesses.
